UNITED STATES PATENT OFFICE.

TIMOTHY C. MURPHY, OF DUBUQUE, IOWA.

ERASER-CLEANER.

1,121,570.

Specification of Letters Patent. Patented Dec. 15, 1914.

Application filed June 1, 1914. Serial No. 842,236.

To all whom it may concern:

Be it known that I, TIMOTHY C. MURPHY, a citizen of the United States, residing at Dubuque, in the county of Dubuque and State of Iowa, have invented certain new and useful Improvements in Eraser-Cleaners, of which the following is a specification.

My invention is designed for use in cleaning erasers and brushes with special reference to cleaning erasers of the chalk dust that collects when the erasers are used in cleaning blackboards in schools and the object is to provide an inexpensive device whereby a large number of these erasers may be cleaned at the same time and in an exceedingly short space of time.

A further object is to dispose of the chalk dust and other dirt after removal from the erasers.

To the end that my invention may be fully understood I will set out in the following specification and illustrate in the drawings forming a part hereof, the manner of construction and mode of operation whereby I accomplish the end sought.

Figure 1 is a plan view of my device with the cover, and trays removed. Fig. 2 is a rear end view, with parts cut away and the rear end removed. Fig. 3 is a front view. Fig. 4 is a perspective view of the tray or jig on which the erasers are placed to be cleaned and showing the hangers. Fig. 5 is a perspective view of the upper tray or cover over the erasers.

Like characters of reference denote corresponding parts in each of the drawings.

The device consists in a rectangular box having the sides 2 and 4, with the bottom 8 and removable top 10 and is set upon legs 12 and 14.

In the end 15 and forward end 16 is journaled a shaft 18. To this shaft are secured blocks 20 and 22, which blocks are preferably of rectangular shape.

Secured to the sides 4 of the box are spring plates 24 which rest upon the blocks 20 and 22. On these plates 24, over the blocks 20 and 22 is set a tray 25, shown in Fig. 4. Upon this tray are placed the erasers 28 to be cleaned. The base of the tray consists of a mesh formed of wires 30 crossing each other at substantially right angles leaving rectangular spaces 32.

At the ends of the tray the mesh is bent upward at substantially right angles, to

prevent the erasers from being shaken off from the tray. To both ends of the tray are fixed standards 35; to these standards are pivoted hooks 36 which hooks are adapted to engage staples 38 in blocks 40 attached to the side of the box to allow the tray to be operated vertically and not be tipped to one side.

For the purpose of preventing the erasers 28 from tipping upon their sides or turning over when they are jigged, there is provided a cover or tray 42 which is preferably constructed of a wire mesh similar to the tray 25. Along the inside of the box 70 are cleats or brackets 44, which are set slightly above the thickness of the erasers 28 and upon these cleats is placed the tray 42.

For the purpose of disposing of the chalk dust and other dirt taken from the erasers the shaft 18 extends out a short distance beyond the end 6 of the box and to the outer end is rigidly mounted a drive wheel 45 having a crank 46 and a handle 48. Over 80 the wheel is loosely set a frame 50 of considerable weight and a trifle wider than the wheel 45 in which frame the wheel 45 rotates. This frame is rigidly bolted together by the bolts 52 and loosely attached to the sides 2 and 4. In this frame is pivoted 85 friction rollers or spools 55 that are adapted to frictionally engage the drive wheel 45. To each one of the shafts of the spools 55 is secured a fan 56.

The manner of operating my device is substantially as follows. The cleaner is set with its rear end in the ventilator of the school room. The tray is placed in the box with its base resting on the plates 24 and the hooks 36 brought into engagement with the staples 38 and the erasers are placed upon the tray 25 with their handles up. Then the tray 42 is placed over the erasers and rests on the cleats 44 and the cover is placed 100 upon the top of the box. The operator grasps the handle 48 and rotates the wheel 45 and since the blocks 22 are rigidly fastened upon the shaft 18 they will rapidly rotate and as they are rotated each corner 105 of the blocks will engage the spring plates 24 and, as the tray 25 rests upon the plates 24, it will be rapidly raised and lowered at each revolution of the shaft 18. This will jar the dust and chalk from the erasers and the heavier particles will drop between the meshes of the tray 25. If the erasers are

rapidly jiggled they will also strike the tray 42 and further jar the dust and dirt from the erasers. At the same time that the shaft 18 is rotated the wheel 45 will also be rotated and, as the spools 55 frictionally engage the wheel 45 and as the fans 56 are rigidly fastened upon the shafts of the spools 55 they will be rapidly rotated, fanning all of the dust out at the back end of 10 the box and the dust and dirt will be carried up the ventilator and disposed of.

It will be seen that the erasers 28 will be cleaned very rapidly and with but a few rotations of the wheel 45 as there will be 15 four jigs at each revolution of the wheel. It will also be seen that the rotation of the fans will be exceedingly rapid from the fact of the difference in the proportion of the circumference of the spools to the circumference of the wheel.

Where there is no ventilator in the room in which this is to be operated, then the frame 50 is removed with the fans 56 and the front and rear ends of the box are closed 25 and the operator rotates the shaft 18 by the crank 46 and the erasers are jiggled up and down in the same manner as before and the chalk dust will settle at the bottom of the box, or the cleaner may be set out of doors 30 and the dust carried away by the wind.

It is evident that other means may be employed for jiggling the erasers and for jiggling them vertically and still be within the spirit of my invention and I do not desire 35 to be limited to my specific construction.

Having now described my invention what I claim is:—

1. In a device of the character described, a box, a tray in the box on which the erasers 40 are sustained while being cleaned, means within the box for giving the erasers and the tray a jiggling motion vertically, and means for preventing the erasers from turning over while being jiggled.

45 2. In a device of the character described, a box, a tray having a mesh on which the erasers to be cleaned are sustained, a shaft journaled in the box, means for rotating the shaft, means attached to the shaft for jiggling the erasers and tray in a vertical manner, and means for preventing the erasers from turning over while being jiggled.

50 3. In a device of the character described, a box, a shaft journaled in the box, blocks

on the shaft, a tray adapted to be engaged 55 by the blocks secured to the shaft, and means for rotating the shaft, whereby the tray is given a jiggling motion.

4. In a device of the character described, a box, a shaft journaled in the box, blocks 60 on the shaft, a tray for holding the erasers to be cleaned and provided with a mesh set over the blocks, a cover over the erasers on the tray and means for operating the blocks to give a jiggling motion to the tray and 65 erasers.

5. In a device of the character described, a box, a tray having a mesh and adapted 70 to support the erasers while being cleaned, a cover over the tray, a shaft journaled in the box, means attached to the shaft to give 75 the tray and erasers a jiggling motion, and means connected with the tray and box for directing the jiggling motion vertically.

6. In a device of the character described, 75 a box, a tray on which the erasers are placed, a cover above the erasers, means for giving the erasers on the tray a jiggling motion vertically between the tray and the cover, a fan, and means for operating the fan to drive the 80 dust from the erasers out of the box.

7. In a device of the character described, a box, a tray on which the erasers are held 85 while being cleaned said tray having a mesh, a shaft journaled in the box, means attached to the shaft for giving the tray and the erasers a jiggling motion, a tray above the erasers to aid in cleaning the erasers and in preventing the turning of the erasers while being cleaned, a fan, means for rotating the 90 fan to drive the dust thrown off from the erasers out of the box.

8. In a device of the character described, a box, a tray on which the erasers to be 95 cleaned are placed, a shaft journaled in the box, means connected with the shaft for giving a jiggling motion to the erasers, a wheel connected with the shaft, a frame over the wheel, and a spool carrying a fan set in the frame and adapted to frictionally engage 100 the wheel and rotate the fan to drive the dust out of the box.

In testimony whereof I affix my signature in presence of two witnesses.

TIMOTHY C. MURPHY.
